CATHARINE A. GRISWOLD, OF NEW YORK, N. Y.

DESIGN FOR THE ORNAMENTATION OF CORSETS.

SPECIFICATION forming part of Design No. 19,235, dated July 30, 1889.

Application filed June 29, 1889. Serial No. 316,095. Term of patent 14 years.

To all whom it may concern:

Be it known that I, CATHARINE A. GRISWOLD, of the city, county, and State of New York, a citizen of the United States, have 5 invented and produced a new and original 10 Design for the Ornamentation of Corsets, of which the following is a full, clear, and exact 15 description, reference being had to the accompanying drawing, forming part of this specification.

The single figure in the drawing represents 20 in side elevation a corset containing my invention.

The leading and special feature of my new 25 design consists in a band or stripe which is curved or bent upon itself about midway its ends, and said ends of which are approximately rectilinear in direction and converge toward each other at their free extremities, 30 said band thus shaped extending from the upper edge of the corset longitudinally downwardly toward the waste-line of the corset.

A represents a corset, which may be in the usual and ordinary form.

B represents a band or stripe, which has the curve or bend b upon itself about midway its ends, and said ends b' and b² of which are approximately rectilinear in direction and converge toward each other at their free extremities, as shown. The band or stripe thus 35 shaped extends from at or about the upper edge of the corset longitudinally downwardly in the direction toward the waist-line of the corset.

What I claim is—

The design for the ornamentation of a corset 40 herein described and shown, the same consisting in a band or stripe B, which has the curve or bend b upon itself about midway its ends, and said ends b' and b² of which are approximately rectilinear in direction and converge toward each other at their free extremities, said band or stripe thus shaped extending longitudinally downwardly from the upper edge of the corset toward the waist-line 45 thereof.

CATHARINE A. GRISWOLD.
